A relative of the invention is my U.S. Patent No. 2,530,212, issued April 4, 1950, which patent is assigned to me, and which patent is incorporated by reference into the present application, and which patent is directed to a core barrel and cutter head structure which may be lowered through a core drill bit and disposed in driving relation therethrough and which structure is designed to permit fluid circulation through the core barrel and along the walls of the bore formed by the core barrel cutting head, the fluid thereafter flowing upwardly with suspended solids and into the main well bore.

UNITED STATES PATENT OFFICE

2,613,918

WIRE LINE CORE BARREL

Thomas Leonard Long, Houston, Tex., assignor,
by mesne assignments, to Johnston Testers,
Inc., Houston, Tex., a corporation of Delaware

Application February 20, 1950, Serial No. 145,229

4 Claims. (Cl. 255—72)

1

This invention relates to oil well tools and particularly pertains to an improvement in wire line core barrel.

In the oil tool industry it is usual to obtain a sample of the drilling formation by the use of a core drill through which is inserted a core barrel suspended upon a wire line and lowered through a supporting drill string to an interlocked position within the drill structure. The core barrel is fitted at its lower end with a circular cutter head to cut a pencil-like core in the formation. The barrel is also fitted with a core catcher which engages the core so that when the core barrel is elevated from within the drill structure the core will be carried with it. It is usual to cause the core barrel to project a considerable distance below the point of protrusion through the drill bit and since circulation of drilling fluid does not normally take place at the operating depth of the core cutter any fluid occurring within the well bore at this depth will be relatively stagnant so that the chips cut during the operation will accumulate within the cylindrical curve formed by the cutter head. This will cause the chips and drilling particles to tend to accumulate in the cutting area and retard the progress of the drilling operation. It is desirable therefore to provide means whereby drilling fluid circulation will be established and maintained at and around the core barrel cutting head thereby flushing the cutting area and removing the chips and other drilled material as the core barrel drilling operation proceeds. It is the principal object of the present invention therefore to provide a wire line core barrel and cutter head structure which may be lowered through a core drill bit and disposed in driving relation therethrough and which structure is designed to permit fluid circulation through the core barrel and along the walls of the bore formed by the core barrel cutting head, the fluid thereafter flowing upwardly with suspended solids and into the main well bore.

The present invention contemplates the provision of a conventional wire line support and locking head for a core barrel and by which a core barrel is carried, the core barrel being fitted with a packer which may be set to pack off the central bore in the drill collar and to thereafter insure that fluid circulation will be continued down through the barrel and through and around the cutter head.

The invention is illustrated by way of example in the accompanying drawings in which:

Figure 1 is a fragmentary view of the upper

portion of a core drill showing the upper portion of a core barrel to be lowered on a wire line and temporarily locked in the core drill.

Fig. 2 is a view in longitudinal section showing the fragmentary portion of the barrel and drill structure forming a continuation of the parts shown in Fig. 1 and indicating the position of the packer within the drill body.

Fig. 3 is a view in longitudinal section and elevation showing the core barrel extending outwardly through the lower end of the drill bit.

Fig. 4 is a fragmentary view in longitudinal section as seen on the line 4—4 of Fig. 2 and shows the length of the core barrel supporting structure occurring above the packer.

Fig. 5 is a view in longitudinal section as seen on the line 5—5 of Fig. 4 and shows the packer structure and its mounting.

Fig. 6 is a view in longitudinal section showing the core barrel structure and the trap valve therefor.

Fig. 7 is a view in transverse section through the structure as seen on the line 7—7 of Fig. 4 and shows the fluid circulating ports above the packer.

Fig. 8 is a view in transverse section as seen on the line 8—8 of Fig. 4 and shows the spline connection between the packer and mandrel and the supporting collar for the packer.

Referring more particularly to the drawings, 10 indicates the driving sub of a standard wire line core drill. This sub is supported from a string of drill pipe not shown. The sub is fitted with a locking shoulder 11 which is engaged by

35 the latch dog 12 and other parts of a latch head generally indicated at 13. Extending downwardly from the sub 10 is a drill collar 14 which is tubular in formation and which at its lower end carries a desired type of drill bit 15. The

40 collar 14 is formed with a central vertical bore 16 which is of a relatively large diameter and through which the wire line core barrel structure 17 is lowered. In this particular case the upper end of the wire line core barrel is formed

45 with a telescoping cylindrical portion 18 which moves with relation to a mandrel 19. At the lower end of the mandrel 19 is a collar 20 and between the cylindrical portion 18 and the collar 20 is a spring 21 which tends to urge the collar

50 downwardly. The collar 20 may be formed with a threaded box to receive a pin 22 formed at the upper end of a perforated nipple 23. This structure may be of a desired length and at its lower end carries a travel collar 24. The travel collar

55 has an outside diameter sufficiently less than

the bore 16 through the drill collar to provide a fluid circulating space 25. When drilling with the bit 15 fluid circulates freely and downwardly through the bore 16 in the collar and outwardly through the eyes of the bit. The lower end of the travel collar 24 is formed with an internally threaded box 26 to receive a pin 27 of a sliding head 28. The sliding head is mounted upon a tubular mandrel 29 which extends upwardly through the member 28 and into a counterbore 30 within the lower end of the travel collar 24. Complementary keyways 31 and 32 are formed in the opposite walls of the mandrel as well as the sliding head and traveling collar. The keyways 32 in the last named members 24 and 28 are longitudinally aligned when the threads on the members 26 and 27 are tightened. The upper end of the mandrel 29 has an externally threaded section 33 which receives a packing head 34. The packing head is here shown as formed with a plurality of square packing grooves 35 which receive O rings 36 to create a fluid seal between the head 34 and the counterbore 30 which permits the mandrel and the head to reciprocate within the counterbore. The lower end of the sliding head 28 rests against an upper packer collar 37 and is formed with a threaded extension 38 which is threaded into a counterbore 39 formed in the upper end of the packer collar 37. The packer collar is associated with a packer sleeve 40 through which the mandrel 29 extends. A lower section of the mandrel is formed with an enlarged portion 41 agreeing substantially in outside diameter with that of the sliding head 28 and thus provides a shoulder 42 against which a lower packing collar 43 may rest. The lower packing collar 43 is suitably associated with the end of the sleeve 40 and is formed with a threaded counterbore 44 which engages threads 45 upon the mandrel. Enlarged lower portion 41 of the mandrel 29 has a threaded section 45' of reduced diameter to receive the box portion 46 of sub 47.

Attached to the sub 47 is a core barrel drill collar 48. This collar carries a cutter head 49 at its lower end. The cutter head is formed with drill fluid exit ducts 50 by which fluid from within the collar 48 may be directed to the cutting area of the cutter head 49. Extending longitudinally within the core barrel collar 48 is a core catcher tube 51 which carries core catching members 52 at its lower end. The upper end of the tube 51 is formed with a plug 53 having a central opening 54 therethrough. A valve seat 55 is formed at the upper end of the opening 54 and within the plug. A valve check ball 56 normally rests upon the seat and is held in position by a spring 57. The spring may be held against longitudinal movement by a pin 58 carried at the upper end of the plug 53. It is obvious that other check valve means might be provided if desired. Attention is directed to the fact that the outside diameter of the core catcher tube 51 is sufficiently less than the inside diameter 59 of the core drill collar 48 and that a fluid circulating space 60 will occur for a purpose to be hereinafter described. It will be understood that the travel collar 24 has a fluid passageway 24' in communication with an opening 34' in the packing head 34 and that the mandrel 29 has a central opening 29' leading downwardly and being in communication with the opening 59 in the core drill collar 48.

In operation it is common practice to lower the cutting drill 15 and its collar on a supporting string of drill pipe and to drill a hole 61 to a

bottom level 62. At this level it is assumed a core is to be cut, this is done by "running ahead" of the bottom level 62 and cutting a core from the formation which has not yet been drilled. The bit 15 is elevated and when this operation is accomplished by the use of a wire line core barrel a structure as generally indicated at 17 is provided. This is lowered through a drill string on a wire line until the latch member 12 of the latch head 13 engages suitable lugs 11 in the driving sub 10. When the wire line core drill is thus positioned its collar 48 will project beyond the lower end of the bit 15 a considerable distance, this distance is usually approximately 27 inches. The drill string is then lowered with the bit to bring the core bit 49 into a drilling engagement with a surface 62 at the bottom of the well bore. The spring 21 in the core bit structure will tend to yieldably urge the bit downwardly at the same time weight is imposed upon the upper packer collar 37 through the perforated nipple 23, the travel collar 24 and the sliding head 28. This will cause the packer sleeve 40 to be compressed longitudinally and expanded circumferentially so that the packer will contact the bore 16 in the main drill collar 14. Prior to the time the packer 40 is set circulation of drill fluid is maintained downwardly through the drill string, the drill collar 14, and outwardly through the water course in the drill bit 15. When the packer sleeve 40 is set downward circulation of drilling fluid is interrupted at the collar and the downwardly flowing fluid will then be forced through the perforations 23' in the perforated nipple 23. Drilling fluid will then pass inwardly through the perforations 23' in the wall of the perforated nipple 23 and then upwardly through the central opening 24' in a traveling head 24 and then through the central opening 29' in the mandrel 29. In view of the fact that the check ball 56 is closed this fluid will then flow downwardly in the passageway occurring between the core barrel 51 and the core drill collar 48 and then outwardly through the usual water course at the bottom of the cutter head of the core barrel. Fluid will then flow upwardly around the core barrel collar 48 and will complete its circulation into the open hole. A core 63 will thus be cut within the core barrel 51 and will be caught by the core catcher finger 64.

It will thus be seen that the improvement in wire line core barrels here disclosed provides simple and effective means to create positive fluid circulation through the core drill and therearound whereby circulation of fluid within the collar of the core drill will take place positively and fluid circulation in the water courses of the core cutting head will take place so that chips may be removed from the bore formed by the cutting head and so that the cutting head will be lubricated sufficiently in the same manner as fluid circulation through the usual drill bit is accomplished.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. In a device for taking cores, a rotatable drill collar, a cutter head on the lower end of the drill collar having a central bore and upwardly ex-

tending passageways in the walls thereof communicating with the interior of the drill collar at points outwardly of the central bore, a core barrel mounted on the cutter head and extending upwardly therefrom and closing off communication between the central bore and the interior of the drill collar and having the interior thereof in communication with the central bore of the cutter head, said core barrel having the walls thereof spaced from the interior of the drill collar to provide an annular space for the passage of fluid to the passageways in the cutter head, a packer on the exterior of the drill collar for engagement with the interior of a drill string or the like, said drill collar having an opening therethrough above the packer communicating the exterior of the drill collar with the interior thereof, and means for connecting the drill collar to a drill string to permit driving of the drill collar.

2. In a device for taking cores, a rotatable drill collar, a cutter head on the lower end of the drill collar having a central bore and upwardly extending passageways in the walls thereof communicating with the interior of the drill collar at points outwardly of the central bore, a core barrel mounted on the cutter head and extending upwardly therefrom and closing off communication between the central bore and the interior of the drill collar and having the interior thereof in communication with the central bore of the cutter head, said core barrel having the walls thereof spaced from the interior of the drill collar to provide an annular space for the passage of fluid to the passageways in the cutter head, and an expandable packer surrounding the drill collar and adapted to be expanded into engagement with the interior of a drill string, said drill collar having an opening therethrough above the packer communicating the exterior of the collar with the interior thereof, means engaging said packer and telescopically but non-rotatably engaging said drill collar for expanding said packer upon lowering of said means relative to the drill collar, and means for connecting the last named means to a drill string or the like to permit driving of the drill collar.

3. In a device for taking cores, a rotatable drill collar, a cutter head on the lower end of the drill collar having a central bore and upwardly extending passageways in the walls thereof communicating with the interior of the drill collar at points outwardly of the central bore, a core barrel mounted on the cutter head and extending upwardly therefrom and closing off communication between the central bore and the interior of the drill collar and having the interior thereof in communication with the central bore of the cutter head, said core barrel having the walls thereof spaced from the interior of the drill collar to provide an annular space for the passage of fluid to the passageways in the cutter head, an expandable packer surrounding the drill collar

and adapted to be expanded into engagement with the interior of a drill string, said drill collar having an opening therethrough above the packer communicating the exterior of the collar with the interior thereof, means engaging said packer and telescopically but non-rotatably engaging said drill collar for expanding said packer upon lowering of said means relative to the drill collar, and means for connecting the last named means to a drill string or the like to permit driving of the drill collar, the second named means including a telescopic but non-rotatable joint resiliently urged into extended position.

4. In a device for taking cores, a rotatable drill collar, a cutter head on the lower end of the drill collar having a central bore and upwardly extending passageways in the walls thereof communicating with the interior of the drill collar at points outwardly of the central bore, a core barrel mounted on the cutter head and extending upwardly therefrom and closing off communication between the central bore and the interior of the drill collar and having the interior thereof in communication with the central bore of the cutter head, said core barrel having the walls thereof spaced from the interior of the drill collar to provide an annular space for the passage of fluid to the passageways in the cutter head, and an expandable packer surrounding the drill collar and adapted to be expanded into engagement with the interior of a drill string, said drill collar having an opening therethrough above the packer communicating the exterior of the collar with the interior thereof, means engaging said packer and telescopically but non-rotatably engaging said drill collar for expanding said packer upon lowering of said means relative to the drill collar, and means for connecting the last named means to a drill string or the like to permit driving of the drill collar, the second named means including a telescopic but non-rotatable joint resiliently urged into extended position, and a retractable latch on the upper portion of the joint for engagement with a drill string for establishing a rotary drive therewith.
